SEWING MACHINE CUTTING ATTACHMENT

Filed Jan. 20, 1930

FIG. 4.

INVENTOR:

ZACHARIA ROUTTENBERG,

By: Otto de Ruygh,
his Atty.

UNITED STATES PATENT OFFICE

ZACHARIA ROUTTENBERG, OF LOS ANGELES, CALIFORNIA

SEWING MACHINE CUTTING-ATTACHMENT

Application filed January 20, 1930. Serial No. 422,049.

This invention relates to devices used for cutting the edge of cloth and the like material handled under the sewing machine to result in a clean cut parallel to the stitching produced by the sewing machine.

One of the objects of this invention is to provide an attachment designed to be applicable to any common sewing machine whereby such a sewing machine is ¹⁰ formed into a combination cutting and sewing machine.

Another object is to provide means whereby the cutting mechanism is automatically held in inoperative position when not used.

¹⁵ Another object is to provide operating means to be made use of at will of the operator to either interengage the cutting and sewing mechanisms for a combined cutting and sewing operation or to disengage the ²⁰ mechanisms to leave the cutting mechanism in inoperative position while the sewing mechanism is in a condition to operate in the normal manner of such mechanisms of any common sewing machine.

²⁵ Other objects will appear from the following description and appended claims as well as from the accompanying drawings, in which—

Fig. 1 is a fragmentary side elevation of ³⁰ the head portion of the free end of the arm of a sewing machine in general outlines having inserted therein a bar with cutting blade to cooperate with the other mechanisms generally found and provided in such a head, a ³⁵ needle-bar with needle and a presser-bar with presser-foot being also roughly outlined in their cooperative positions in relation to the cutting mechanism of this new attachment.

Fig. 2 is a section on line 2—2 of Fig. 1 ⁴⁰ through the needle-bar and through the cutter-bar illustrating an engaging pin and knob in inoperative position and in top plan view.

Fig. 3 is a fragmentary front elevation of the cutting blade attached to the end of the ⁴⁵ cutter-bar.

Fig. 4 is a horizontal section similar to the one illustrated in Fig. 2, illustrating a slightly modified form of engagement.

While combination cutting and sewing ⁵⁰ machines are known, the principal feature

of this invention is to provide an attachment by which any common sewing machine can be transformed into such a combination cutting and sewing machine, at the same time leaving the sewing machine in a condition that it can still be used as such with the cutting mechanism in inoperative position.

Any sewing machine is commonly provided with a needle bar as indicated at 4 with a needle 5 attached to the lower end. ⁶⁰ A presser-bar 6 is provided at its lower end with the presser-foot 7.

A cutter-blade 8 is provided on this new attachment in such a manner as to become disposed sidewise of the presser-foot 7. The ⁶⁵ cutter-blade 8 is attached to the lower end of the cutter-bar 9, which is shiftably mounted on the head 10 on the front end of the arm of a sewing machine, not shown in the drawings. ⁷⁰

The head on the free end of the arm of different sewing machines may be of different shapes and designs, and the outline used in the drawings together with the manner or parts disclosed for holding the cutter-bar to ⁷⁵ the head must therefore not be considered final or exclusive since for the above reason such parts must vary on different sewing machines especially so since this new attachment is to be used as an additional mechanism to be applied to any already existing ⁸⁰ sewing machine.

The form of the cutter-bar too, therefore, must be different for the attachments for different sewing-machines. ⁸⁵

As illustrated in the drawings, the cutter-bar 9 is bent in its lower portion as indicated at 13, to bring the attached cutter-blade 8 into the most desirable position in relation to the needle and to the presser-foot, ⁹⁰ however, for the above reasons the bending or forming of the bar 9 must depend on existing conditions in sewing machines.

The upper end 14 of the cutter-bar is bent, and a spring 15 is inserted between this bent ⁹⁵ end 14 and the top of the head 10 of the arm of the sewing machine, to hold the cutter-bar with the cutting blade in inoperative position and adapted to yield for the downward cutting movements when the cutting attach- ¹⁰⁰

ment is operatively interconnected with the sewing mechanism.

A catch or engagement is illustrated in Fig. 2 in detail, partly also distinguishable in Fig. 1. The support or member 16 is shiftably and turnably mounted in the cross-head 17, a spring 18 being provided on the back of the cross-head whereby the member 16 is normally pressed in the direction of the arrow 19. The member 16 is provided with an engaging-pin 20, which abuts against the outer or front face of the cross-head 17 when in inoperative position in which position the whole engagement is illustrated in Figs. 1 and 2, while this pin can be made to pass into the hole 21 in the cross-head 17 and into the slot 22 of the cutter-bar 9 in engaging position.

To bring the engagement into inoperative position, the member 16 is simply grasped by the knob 23 and drawn against the tension of the spring 18 until the pin 20 is withdrawn from the slot 22 and hole 21, when the whole engagement may simply be turned either to the left or to the right until the free end of the pin 21 comes to abut against the face or full material of the cross-head 17, in which position the engagement will remain under the tension of the spring 18.

The slot 22 is provided since a comparatively short movement is sufficient for the cutting operation while the needle-bar 4 is normally required to move comparatively far above and below the needle-plate of the sewing machine for its proper operation.

The cross-head 17 is secured to the needle-bar 4 in any convenient manner, a set-screw 24 being indicated in the drawings but various other means may be used for this purpose, depending principally on the construction of the different or suitable parts of the various sewing-machines.

A slightly modified form of engagement is illustrated in Fig. 4. The block 25 is secured to the cross-head 17 by the screw 26. The pin 27 is shiftable within the block 25 under the tension of the spring 28, having notches 29 and 30 by which the pin can be held in its different adjusted positions, for, either interengaging the cutter and needle bars, or interrupting such engagement so that the needle-bar can move independently of the cutter bar. The locking-pin 31 under the tension of the spring 32 serves to hold the pin 27 in its predetermined positions by means of the notches 29 and 30.

Having thus described my invention, I claim:

1. In a cutting attachment, in combination with the needle-bar and the head of the arm of a sewing machine, a cutter-bar shiftably mounted on said head with its lower cutting end in operative relation to the lower end of the said needle-bar, means for normally holding the cutter-bar in its uppermost inopera-

tive position, a cross-head adjustably mounted on the said needle-bar extending sideways to the cutter-bar and having an aperture, the cutter-bar having a slot in alignment with said aperture, and an engagement shiftably and turnably mounted on said cross-head having a pin-portion adapted to extend through the said aperture and slot for operatively engaging the said needle-bar with said cutter-bar and including a tension means for normally pressing the engagement against the cross-head in engaging position as well as in inoperative position.

2. In a cutting attachment, in combination with the needle-bar of a sewing machine, operating means extending from the needle-bar in a sidewise direction and including an engaging member, and a cutter-bar having a slot to slidably receive the said engaging member and adapted to be operated by the needle-bar when said engaging member comes into contact with an end wall of said slot.

In testimony that I claim the foregoing as my invention I have signed my name.

ZACHARIA ROUTTENBERG.
